FUEL INJECTION SYSTEM FOR INTERNAL-
COMBUSTION ENGINES

George Amery, London, England

Application December 28, 1936, Serial No. 117,964
In Great Britain December 31, 1935

6 Claims. (Cl. 123—140)

This invention comprises improvements in or relating to fuel injection systems for internal-combustion engines.

The invention relates to internal-combustion engines of the compression ignition type. I have found that in such engines it is desirable that the pressure of injection of fuel should be a function of the speed of the engine. The employment of a higher injection pressure tends to reduce the "delay period" which exists between the commencement of the admission of fuel and the commencement of its ignition. At higher engine speeds the time available for ignition is reduced. Consequently the reduced "delay period" resulting from a higher injection pressure suits the conditions of high engine speed.

In United States Patent No. 2,053,312 there is described an injection system in which there is provided a relief valve the setting of which determines the maximum injection pressure.

According to the present invention in a fuel injection system in which a relief valve is provided for limiting the maximum injection pressure means are provided for modifying the pressure at which the relief valve will operate in accordance with the engine speed.

The means for modifying the relief valve pressure may comprise a centrifugal governor operatively connected to a member for resisting the opening of the relief valve.

There may further be provided in combination with the above means for delivering fuel under injection pressure to the injection devices such that the fuel delivery in a given time is proportional to engine speed. The relief valve and means for delivering fuel at injection pressure may be each connected to a fuel delivery conduit which is common to a plurality of injection devices, separate means being provided to determine the order and time at which the injection devices operate for the injection of fuel.

In one form the fuel injection devices are of a type in which the admission and termination of fuel injection is determined by the application or removal of fluid pressure to a controlling piston.

Preferably the controlling piston is a closing piston, the application of fluid pressure to which shuts the valve and the means to determine the order and time at which the injection devices operate comprises a distributor which distributes fluid under pressure to the closing pistons from a branch connection of the fuel delivery conduit so that the closing pressure is proportional to the fuel injection pressure.

The relief valve may comprise a valve member,

a spring to resist the opening of the valve member, centrifugal governor weights and means for rotating the same and operative connections between the governor weights and the spring to sustain the spring against the pressure of the valve member under the influence of the centrifugal force exerted upon the governor weights.

The following is a description by way of example of one form of fuel injection system in accordance with the invention:

Referring to the accompanying drawings

Figure 1 is a diagram of the connections of the system as a whole;

Figure 2 is a longitudinal central section through a relief valve in accordance with the invention, and

Figure 3 is a cross-section upon the line 3—3 of Figure 2.

Referring to the drawings in Figure 1 it represents a fuel pump for delivering fuel under pressure from a fuel tank 12 to a pipe line 13 at injection pressure. The pipe line 13 is provided with branches 14 to fuel injectors 15 allocated one to each cylinder of the engine. The branches 14 enter chambers 16 in the fuel injectors where the fuel, under the injection pressure surrounds a needle valve 17 bearing on a seating 18. The needle valve has a shoulder 19 which is subject to the fuel pressure and the pressure tends to lift the valve 17 off its seating. The pump 11 is such as to maintain a uniform continuous pressure in the fuel supply pipe 13 and around the injector needle valves 17. Each injector has, moreover, an enlarged head which constitutes a closing piston 20 to which fluid under pressure is admitted through a distribution pipe such as 21 and in addition there is a spring 22 which assists to keep the needle valve 17 closed.

It will be understood that each of the fuel injector nozzles 15 is secured in the combustion chamber of an engine cylinder in an appropriate position, as is well known. Drain pipes 23 serve to carry away any fluid which leaks past the pistons 19 or 20.

Connected to the pipe line 13 there is a relief valve 24 which determines the injection pressure and the pump 11 is made of sufficient capacity to ensure that even at full load fuel will be able to escape through the relief valve 24. Drainage 50 from the relief valve 24 and from the drainage pipes 23 can, if desired, be led back to the fuel tank 12, as indicated by pipe 54. The construction of the relief valve 24 is hereinafter detailed.

In order to determine the distribution of fuel

under pressure to the closing pistons 20 of the fuel injection nozzles a distributor 25 is provided. In the connections as drawn in Figure 1 the distributor 25 is supplied with fuel under pressure by a branch 26 from the fuel conduit 13 but the distributor might be provided with an alternative source of fluid under pressure if desired so long as an adequate quantity and pressure of fluid are provided to operate the pistons 20. It will be observed that the closing pistons 20 are of larger area than the shoulders 19 which constitute the opening pistons for the needle valve 17 and therefore even a lower pressure than the injection pressure applied in the chamber 16 may suffice to keep the needle valve 17 of each fuel nozzle shut. If, however, pressure is released from behind the closing piston 20 the needle valve will immediately open due to the pressure of the injection fuel in the chamber 16. Four separate fluid distribution conduits 21, 31, 41, 51 are provided for the four injector nozzles 15 and each of these is led to a separate distribution valve casing 32, 33, 34, 35 on the distribution unit 25. The details of the distribution unit 25 in themselves form no part of the present invention. It is sufficient here to state that each of the valve casings 32, 33, 34, 35 contains a piston valve operated by a cam within the unit 25 for determining the admission of fuel under pressure to the closing pistons 20 and preferably this cam is provided with means for advancing and retarding the time of the operation and also for modifying the period during which the pressure is applied to the pistons 20.

Referring to Figures 2 and 3, which show the relief valve 24 in detail, the valve comprises a hollow casing having a projecting bearing 55 at one end through which passes an operating shaft 56 driven at a speed which is proportional to the engine speed, for example from the usual valve-operating cam shaft of the engine. The pump 11 may be operated by the same shaft, as indicated in Figure 1.

The shaft 56 is supported in ball bearings 57, 58 and has an enlarged head 59 within the casing 24 which is slotted diametrically as indicated at 60. Two pivot pins 61, 62 cross the slot 60 and each supports a governor lever 63 bearing a weight 64. The two levers are similar to one another and are disposed at opposite sides of the axis so as to be in balance with one another. The levers each have an abutment 65 which supports a ball race 66 taking the reaction of a valve spring 67. The valve spring 67 is co-axial with the shaft 56 and bears on a carrier 68 rotatably received in the end of head 59, in the opposite end of which there is slidably mounted the stem of a relief valve 69. The relief valve has a head 70 within the carrier on which bears a spring 71 so that the relief valve is pressed as far as possible out of the carrier, towards the right as shown in Figure 2.

The relief valve 69 bears on a seating 71 in a valve block 72 which fits into and closes the end of the casing 24 of the relief valve. The valve block 72 is adjustably retained in place by a screwed ring 73 and it is centrally bored with the passage 74 connecting the seating 71 with the pipe 75 which is a branch of the fuel supply conduit 13. Consequently fuel under pressure bears upon the end of the relief valve 69 but the opening of the relief valve is resisted by the spring 67, the reaction of which is taken by the governor levers 63.

The carrier 68 has a projection 76 at the end of

which is spaced somewhat from the adjacent thrust plate of the ball bearing 66. In this way when the valve 69 is opened a certain distance the lost motion between the projection 76 and the thrust race 66 will have been taken up and further movement of the valve 69 will be resisted, not by the spring 67 but by the spring 71 which is a stiffer spring than the spring 67.

The valve 69 has a head 77 which is surrounded by an enlarged portion 78 of the bore in which the valve works and beyond the enlarged portion 78 there is a short section of bore 79 which is of such a size as to closely fit the head 77. Beyond the section 79 is a second enlargement 80 which is connected by a channel 81 to the drain pipe 54. Moreover, the conduit 74 which is connected to the branch 75 and conveys fuel pressure to the end of the valve 69 receives an extension 82 on the end of the valve 69.

The governor levers 63 are also provided with abutments 83 which bear against stop pins 84. The stop pins 84 are slightly eccentric on their shanks 85 which find a bearing in the head 59 of the shaft 56. By rotating the stop pins the stops 83 can be adjusted so that the governor levers 63 are pressed against the stop pins evenly by the spring 67 when the driving shaft 56 is not revolving.

The pump 11 which delivers the fuel under pressure to the conduit 13 is of such a type as to deliver fuel at a rate proportional to engine speed.

The operation of these parts is as follows:—

The pump 11 delivers fuel under pressure to the conduit 13 and owing to the operation of the distributor 25 pressure is relieved from the back of each of the pistons 20 of the various fuel injection nozzles in turn. This allows fuel under pressure to lift the needle valves 17 by acting on the shoulders 19 and to inject fuel into the engine cylinders at the appropriate times. The pressure generated by the pump 11 is limited by the relief valve 24.

At starting it is necessary to have a high injection pressure for the first few revolutions until the engine gets under way. This is accomplished by the extension 82 of the relief valve 69, which being of smaller area than the head 77 ensures that the valve will only open under a pressure in excess of that allowed by the head 77. As soon as the valve 69 has been lifted off its seat sufficiently for the extension 82 to clear the passage 74 the fuel pressure acts on the full area of the head 77, which is so proportioned that at this time the head has entered the portion of the bore 79 which fits it. Consequently the fuel pressure, acting on this larger area forces the valve 69 further to the left compressing the spring 67 until almost the whole of the lost motion between the extension 76 and the thrust plate 66 has been taken up. In this position the head 77 just passes the constricted portion 79 and reaches the enlargement 80 of the bore in which the relief valve works. Further movement of the relief valve 69 will open an annular area between the edge of the constricted portion 79 and the edge of the head 77 of the valve thus permitting fuel to escape to the drain channel 81. In this position of the relief valve it maintains a predetermined minimum pressure of injection (i. e., the injection pressure required at idling speeds) and in this position the end of the projection 76 is not in actual contact with the adjacent thrust plate of the bearing 66 although close to it, and the centrifugal force tending to open the governor weights is

balanced by the spring 61. However, when the engine speed increases the governor weights 64 will open outwardly slightly thus forcing the thrust race 66 against the projection 76.

5 The spring 171 is made of such stiffness that at all normal engine speeds it is unable to yield and the connection between the governor weights and the valve head 77 is in effect rigid. This will mean that the pressure in the pipe 13 is proportional to the square of the engine speed because the force on the governor weight 64 will be proportional to the square of the engine speed. Consequently the injection pressure will be sufficient at the increased speed to maintain the same fuel delivery through the valve 17 notwithstanding the shorter time during which the valve is opened. For a given setting of the distributor therefore the engine will continue to receive the same amount of fuel as before. The regulation of the admission of fuel in accordance with the load is accomplished by the distributor 25 as above described. At engine speeds leading to a fuel pressure in excess of the strength of spring 171, this spring will yield and thus prevent over-straining of the pipework and other parts by excessive fuel pressure.

I claim:

1. In a fuel injection system the combination of a pressure conduit, a relief valve for limiting the maximum injection pressure in said conduit, means for modifying the pressure at which the relief valve will operate in accordance with the engine speed, said means comprising a centrifugal governor operatively connected by resilient means to the relief valve, said relief valve comprising a valve member having a stem extension of smaller diameter than its normal head and fitting into said pressure conduit whereby an increase of injection pressure is provided at the commencement of operation.

2. In a fuel injection system for an internal-combustion engine the combination with a fuel-pump and means to distribute fuel therefrom to the engine, of a relief-valve casing having a bore connected to the fuel distribution means, a

valve-plunger in said bore capable of uncovering a relief-opening after a predetermined movement, a spring opposing the movement of the valve-plunger, a reaction-member on which the spring bears, a stop mounted to move with the valve 5 plunger in line with a face associated with the reaction member so as to limit the movement of the valve-plunger against the spring and so located as to come into engagement with said face approximately simultaneously with the uncovering of the relief-opening and a centrifugal governor having centrifugally actuated elements which are operatively connected to the reaction member to sustain the same.

3. A fuel injection system as claimed in claim 15 2, wherein the said spring bears on the head of a carrier for the valve-plunger and an overload spring is interposed between the carrier and the valve-plunger.

4. A fuel injection system as claimed in claim 20 2, wherein the valve-plunger has an extension capable of entering an extension of the bore in the relief-valve casing of smaller diameter than the main part of the bore, so as to give an extra high injection pressure at starting.

5. In a fuel-injection system the combination of fuel-injection devices, fuel pressure supply means, a supply system connecting the supply means to the injection devices, a relief-valve for closing a port in said supply system, a relief-valve 30 carrier-member, a centrifugal governor, resilient means interposed between the carrier member and the centrifugal governor and a stop on the carrier for limiting the extent of yield of said resilient means, said governor being the reaction-providing element against the opening of the relief valve after the engagement of the stop.

6. In a fuel-injection system as claimed in claim 5 the provision of a second resilient means interposed in series between the carrier member 40 and the valve, said second resilient means being substantially stronger than the one between the carrier member and the governor.

GEORGE AMERY. 45
